UNITED STATES PATENT OFFICE.

PHILIP S. KIMBALL, OF MILFORD, MASSACHUSETTS, ASSIGNOR TO F. W. MANN COMPANY, OF MILFORD, MASSACHUSETTS, A CORPORATION OF MASSACHUSETTS.

JACK.

Application filed July 7, 1925. Serial No. 41,860.

The present invention relates to an improvement in jacks.

The object of the invention is to reorganize and improve the construction of jacks, and more particularly screw jacks. The invention consists in the jack hereinafter described and particularly defined in the claims.

In the drawings illustrating the preferred form of the invention, Fig. 1 is a sectional elevation of a jack; Fig. 2 is a plan; Fig. 3 is a section taken on the line 3--3, Fig. 1; and Fig. 4 is a sectional elevation of the jack head.

The illustrated embodiment of the invention is described as follows: The jack comprises a body 10 having a foot 11 integral therewith. The body of the jack is cylindrical in form at the bottom, and enlarged at the top to receive two bevel gears by which the jack is operated. The pillar 12 of cylindrical form extends upward from the foot or base, and receives the screws. There are two of these screws, an outer screw 13, and an inner screw 14, the former being screwthreaded through the hub of the bevel pinion 15, and the latter being screwthreaded through the head 16 of the outer screw 13. The outer screw 13 is provided with a longitudinal groove 17, extending from end to end thereof. This groove receives a roll 18 supported in the housing of the pillar and pressed into the groove 17 of the outer screw 13 by means of the spring 19, the spring taking against the cotter pin 20 which holds it in place. The pressure of the spring 19 on the roll 18 operates to hold the outer screw 13 from turning except when its tendency to turn is great enough to push the roll or detent 18 out of the groove 17. A driving pinion 21 meshing with the driven pinion 15, is used to rotate the driven or lifting pinion 15. It is pinned on the shaft 22, which is supported in bearings 23, 24, of the housing at the top of the pillar 12. By turning the shaft 22, the driving pinion 21 is rotated, and it in turn rotates the driven or lifting pinion 15, which operates either to directly lift the outer screw 13 while the latter is held in place by the detent 18, or it turns the outer screw and thereby causes the inner screw to be raised.

The driving shaft 22 is provided with a head 25, to which is pinned the fork 26

by means of the riveted pin 27. The fork 26 is formed on the end of a sleeve 28, which receives the detent 29 adapted to engage the recess 30 in the head 25, being pressed in a direction to engage such recess by the spring 31, received in the sleeve as shown in Fig. 1. This enables the sleeve 28 to support itself in the position shown in Fig. 1, on the head 25. The sleeve 28 is provided at its outer end with a square hole 32, adapted to receive the head 33 of an operating shaft 34, worked by a crank handle in the usual way.

The driven or lifting pinion 15 is preferably made of bronze and supported on its under side by a ball bearing 35. The upper end of the pinion hub is reduced in size at 36, and received in a hole in the cover plate 27, secured to the top of the housing by means of the screws 38. This affords a good support for the driven or lifting pinion 15, and holds it in proper position with relation to the screws and the driving pinion, and as well supports the jack screws in correct position in the jack.

The top of the jack is provided with a head 39 with a roughened surface, adapted to cause it to engage and hold almost any sort of a surface of the body to be lifted by the jack. Incidentally, this operates to lock the inner screw from rotation, which is necessary in order to secure the desired operation of the jack.

The upper surface of the head 39 is provided with V-shaped grooves arranged at right angles to each other, thus forming pyramidal projections, and the center of the upper surface of the head is cupped so that when the head engages a convex body, it tends to seat itself securely on the head of the inner screw 14.

The housing 40, supported by the pillar, completely encloses the driving and driven pinions, and affords an oil well into which the lower edge of the driving pinion 21 may dip so that it may continuously carry oil to the teeth of the upper pinion. This oil well is formed by the outer portion of the housing 40 and the inner web 41, which extends upward from the bottom of the outer housing to the floor 42 of the housing for the driven pinion. This floor is spot-faced to receive the lower raceway of the ball bearing, the upper raceway of which rests directly upon the balls and comes directly in engagement

on its upper side with the driven or lifting pinion.

The cover plate 37 serves the double function of closing the housing and affording a bearing to contribute to the support of the driven or lifting pinion.

It will be observed that without the detent and without holding the inner screw stationary, both the screws and the driven pinion turn together. If, however, the detent be operative, as it normally is, it will be seen that it will hold the outer screw from rotation during the first part of the lifting operation. This screw will continue to be held from rotation until the end of the thread groove of the outside screw 13 is engaged by the end of the thread of the driven or lifting pinion 15. Then further rotation of the driving pinion operates to turn the outer screw, and the inner screw, being held from rotation by engagement of its head with the object or thing to be lifted, rises from the inner screw and further lifts the weight or thing resting upon it. The latter is headed at the bottom so that it can be turned only to a certain determined height. In lowering the jack, the outer screw first descends until the upper end of the thread of the outer screw engages the lifting or driving pinion 15, whereupon the driving pinion picks up the outer screw 13 and rotates it, and the inner screw, being held from rotation as described, is then lowered by the turning of the outer screw thereon.

What is claimed is:—

1. A jack comprising a frame, two screws, an inner screw and an outer screw, the inner screw being threaded inside of the outer screw, a driving pinion threaded on the outside of the outer screw, the outer screw being provided with a longitudinal groove in

its exterior, a spring pressed detent engaging such groove in the outer screw and holding it from rotation at times.

2. A jack having, in combination, a frame, a screw, a nut engaging the screw, a second screw screwthreaded inside the first screw, the outer screw being provided with a longitudinal groove, a cylindrical roll adapted to engage the groove in the outer screw and to hold the latter from rotation except when excessive pressure is exerted thereon, and yielding means for holding the roll or detent in position.

3. A double screw jack having, in combination, an outer screw provided with an external and an internal thread, a nut for engaging the external thread, a second screw engaging the internal thread, the external thread being provided with stops at both ends and with a longitudinal groove, a frame-work for supporting the parts provided with a detent recess, a cylindrical detent supported in the detent recess, a spring backing up the detent and received in the detent recess, and means for holding it therein.

4. A double screw jack having, in combination, an outer screw provided with internal and external threads, a nut engaging the outer thread, said outer thread being provided with a longitudinal groove, a frame, a detent-boss on the side of the frame, a detent recess in the boss, a cylindrical detent loosely mounted in the recess, a spring, and means for holding it in the recess to press the detent into the groove in the outer screw except when pressed outwardly by pressure of the walls of the groove thereupon.

In testimony whereof I have signed my name to this specification.

PHILIP S. KIMBALL.
